UNITED STATES PATENT OFFICE.

LEWIS ERNEST KEIL, OF ST. LOUIS, MISSOURI, ASSIGNOR TO ST. LOUIS CAR COMPANY, OF ST. LOUIS, MISSOURI, A CORPORATION OF MISSOURI.

SPRING-SUPPORT.

1,237,053.

Specification of Letters Patent. Patented Aug. 14, 1917.

Application filed April 17, 1917. Serial No. 162,670.

To all whom it may concern:

Be it known that I, LEWIS E. KEIL, a citizen of the United States, and a resident of St. Louis, in the State of Missouri, have 5 invented a new and Improved Spring-Support, of which the following is a full, clear, and exact description.

The invention relates to cars, and its object is to provide a new and improved 10 spring device arranged to cause the course of the car body to remain in nearly a straight line without up or down motion to insure easy riding especially in case of unevenness in the track which tends to cause 15 the truck frame to move upward and downward and thereby force the car body upward or pull the same downward. Another object is to provide means which transmits from the car truck to the car body the de- 20 sired push or pull necessary to cause the car body to move forward or stop from motion with the truck. Another object is to make provision for the extension in the length of the main elliptical springs caused by their 25 deflection under varying loads. A further object is to simplify the spring and draft mechanism of the truck to permit convenient removal of worn out or broken parts and replacement thereof by new ones. 30 Other objects will appear from the further detailed description of the spring support.

In order to accomplish the desired result, use is made of two spring devices, of which one is lighter than the other, the stronger 35 spring device being mounted on the truck and supporting the lighter spring device, and the lighter being adapted to support the car body, and a radius rod pivotally engaging the truck with the said lighter 40 spring device to transmit from the car truck to the car body the desired push or pull.

A practical embodiment of the invention is represented in the accompanying drawings forming a part of this specification, in 45 which similar characters of reference indicate corresponding parts in all the views.

Figure 1 is a side elevation of the car truck provided with the spring device;

Fig. 2 is a plan view of the same;

Fig. 3 is an enlarged side elevation of one 50 of the spring supports as applied;

Fig. 4 is a cross section of the same on the line 2—2 of Fig. 3 and showing more particularly the fastening of the elliptical spring to the journal box; 55

Fig. 5 is a plan view of the spring support as applied;

Fig. 6 is a cross section of the same on the line 4—4 of Fig. 5 and showing more particularly the lighter spring device; and 60

Fig. 7 is a perspective view of the helical spring casing, the spring support and the follower in disassembled position.

To each end of each side beam 10 of the truck frame is bolted or otherwise secured 65 a bracket 11 forming an integral part of the main or bearing portion 12 of the journal box in which the corresponding journal of the car axle 13 is journaled, the car axle carrying the car wheels 14 in the usual manner. The spring supports of each truck are alike in construction and it suffices to describe but one in detail. The top of the bearing portion 12 of each journal box is provided with a tongue 15 on which rest 70 the butt ends of the superimposed leaves of a quarter elliptical spring 16 fastened in place on the tongue 15 by a suitable clip 17 carried by the bracket 11.

The free end of the quarter elliptical 80 spring 16 extends through a side opening 20 into a spring casing 21 adapted to be bolted or otherwise fastened to the under side of the car body 22, as indicated in Fig. 1.

On the top of the free end 18 of the 85 elliptical spring 16 rests a cup 25 in which is seated the lower end of a helical spring 26 engaging with its upper end the under side of the top of the spring casing 21, as plainly shown in Fig. 4. The cup 25 is 90 slidably mounted with the spring casing 21 and the said cup is provided with an integral depending rod 27 extending through an opening in the free end 18 of the elliptical spring 16. The rod 27 extends a distance below the bottom of the spring casing 21 and on it is held a cup-shaped follower 28 seated on a key 29 removably held in the 95

lower portion of the rod 27 to allow removal of the follower 28. On this follower 28 rests a second helical spring 30 abutting at its upper end against the underside of a 5 cup 31 formed integrally on the under side of the spring casing 21. As the upper helical spring 26 is seated on the cup 25 which latter rests on the free end of the elliptical spring 16 and the latter is practically not 10 appreciably deflected under a light load, it is evident that the downward movement of the spring casing 21 compresses the upper helical spring 26, and as the lower helical spring 30 is supported from the free end of 15 the elliptical spring 16 by the use of the follower 28, the rod 27 and the cup 25 it is likewise evident that this spring 30 is compressed and simultaneously with the compression of the spring 26 on the downward 20 movement of the spring casing 21. By the arrangement described a double or tandem helical spring device is mounted on the free end 18 of the quarter elliptical spring 16. The quarter elliptical spring 16 is consider- 25 ably stronger than the combined strength of the two helical springs 26 and 30, and the helical spring device operates when the truck is carrying a light load while the elliptical spring 16 operates when the truck 30 is carrying a load which exceeds the strength of the helical spring device. Thus the helical spring device deflects for a limited distance and then becomes solid and with but a slight deflection on the part of the ellipti- 35 cal spring 16. When the load is increased then the elliptical spring 16 solely carries the load.

The side of the spring casing 21 having the entrance end 20 for the free end 18 of 40 the elliptical spring 16 is provided with lugs 40 carrying a pivot pin 41 engaging one end of a draft bar or radius rod 42 pivotally connected by a pivot pin 43 with the upper end of the clip 17 used for fastening 45 the elliptical spring 16 to the bearing portion 12 of the journal box, as previously mentioned. The draft bar 42 transmits the forward or backward motion of the car truck to the car body 22 and the said draft 50 bar 42 extends above the journal box and the elliptical spring 16 and hence the latter and the draft bar are wholly independent one of the other and each is free to function without interference by the other and irrespective of the varying loads.

It is expressly understood that by the spring arrangement shown and described, the helical springs will deflect for a limited distance, that is, the maximum distance 60 which is allotted to them for deflection, with a comparatively small increase in load over the load which is superimposed upon them, while the quarter elliptic spring being considerably stronger than the sum of

the two helical springs will deflect only 65 slightly leaving the maximum deflection of the quarter elliptic spring available for increased loads greater than the load necessary to cause the helical springs to deflect their allotted amount; that is, to have practically two sets of springs on the trucks; 70 one set of springs to operate when the trucks are carrying but light loads and the other set of springs to operate when the truck is carrying loads which exceed the capacity of the light load springs. 75

By supporting the car body in the manner described, an easy riding thereof is insured especially when the truck wheels pass over uneven portions of the track, and thus 80 the car body tends to remain more nearly in a straight line without causing undue up and down motion.

It will be noticed that by combining the 85 spring support with the draft device the desired push or pull is transmitted to the car body from the truck.

The several parts of the spring devices and the draft mechanism can be readily 90 assembled or disassembled for repairs or other purposes, and the simplification of the parts and the combination of the draft mechanism of the truck with the spring devices thereof reduces the weight of the entire truck unit to a considerable extent. 95

The journal box shown and described forms the subject matter of another application and hence its special construction is not claimed in this application.

The car truck shown in Figs. 1 and 2 is 100 provided at each side with a suitable brake mechanism.

Having thus described my invention, I claim as new and desire to secure by Letters Patent:—

1. In a car truck, an elliptical spring device mounted on the truck frame, and a tandem helical spring device mounted on the free end of the said elliptical spring device and adapted to carry the car body, the said 110 tandem helical spring device being lighter than the said elliptical spring device and becoming solid under a load which exceeds the strength of the light spring device.

2. In a car truck, a rigid truck frame having a journal box permanently attached thereto, an elliptical spring attached to the said journal box, a tandem helical spring device adapted to support the car body and carried on the free end of the said elliptical 120 spring, the latter being stronger than the tandem helical spring device, the latter deflecting for a limited distance and becoming solid under a load which exceeds the strength of the light spring device.

3. In a car truck, a rigid truck frame having a journal box permanently attached thereto, a quarter elliptical spring attached

to the said journal box, a spring casing for the car body to rest on and tandem helical springs mounted in the said casing, one of the springs resting on the free end of the 5 said elliptical spring.

4. In a car truck, a rigid truck frame having a journal box permanently attached thereto, a quarter elliptical spring attached to the said journal box, a spring casing for 10 the car body to rest on, helical springs one above the other, the said casing resting on the said springs, and a support engaged by the said springs and resting on the free end of the said elliptical spring.

15 5. In a car truck, an elliptical spring device mounted on the truck frame, a helical spring device mounted on the free end of the said elliptical spring device and adapted to carry the car body, the said helical spring 20 device being lighter than the said elliptical spring device and becoming solid under a load which exceeds the strength of the light spring device, and a radius rod connecting the truck frame with the said helical spring 25 device to transmit the draft from the truck to the car body.

6. In a car truck, a rigid truck frame having a journal box permanently attached thereto, a quarter elliptical spring attached 30 to the said journal box, a spring casing for the car body to rest on, helical springs one above the other, the said casing resting on the said springs, a support engaged by the 35 said springs and resting on the free end of the said elliptical spring, and a radius rod connecting the truck frame with the said spring casing to transmit the draft from the truck to the car body.

7. In a car truck, the combination of two 40 spring devices of different strength, the stronger spring device being mounted on the truck and supporting the lighter spring device and the latter being adapted to support the car body, and a radius rod pivotally connecting the truck with the said lighter spring 45 device.

8. In a car truck, an elliptical spring attached to the car truck, a helical spring casing on which a car body is adapted to rest, 50 the said casing being open at one side for the passage of the free end of the said elliptical spring, an upper helical spring and a lower helical spring, the said springs carrying the said casing, a spring support slidable in the 55 said casing and supporting the upper spring, the said support resting on the free end of the said elliptical spring and having a depending rod, and a follower held on the lower end of the said rod and supporting the 60 said lower helical spring, the upper end of which bears against the underside of the casing.

9. In a car truck, an elliptical spring attached to the car truck, a helical spring cas-

ing on which a car body is adapted to rest, 65 the said casing being open at one side for the passage of the free end of the said elliptical spring, an upper helical spring and a lower helical spring, the said helical springs carrying the said casing, a spring support 70 slidable in the said casing and supporting the upper spring, the said support resting on the free end of the said elliptical spring and having a depending rod, a follower held on the lower end of the said rod 75 and supporting the said lower helical spring, the upper end of which bears against the underside of the casing, and removable means on the said rod and engaging the said follower to removably hold the latter in position on the rod.

10. In a car truck, an elliptical spring attached to the car truck, a helical spring casing on which a car body is adapted to rest, 85 the said casing being open at one side for the passage of the free end of the said elliptical spring, an upper helical spring and a lower helical spring, the said helical springs carrying the said casing, a spring support 90 slidable in the said casing and supporting the upper spring, the said support resting on the free end of the said elliptical spring and having a depending rod, a follower held on the lower end of the said rod and supporting the said lower helical 95 spring, the upper end of which bears against the under side of the casing, and a radius rod pivotally connecting the said spring casing with the car truck.

11. In a car, the combination of a truck 100 frame, a car body, journal boxes mounted on the said truck frame, a spring mounted on each journal box, a connection between the free end of the said spring and the car body, and a draft bar connecting the said 105 journal box with the corresponding connection of the spring with the car body.

12. In a car, the combination of a truck frame, a car body, journal boxes rigidly mounted on the said truck frame, elliptical 110 springs mounted on the said journal boxes and extending lengthwise of the car, spring casings attached to the car body and each provided with tandem springs connected with the free end of the corresponding 115 elliptical spring and draft bars extending lengthwise of the car and connecting the said journal boxes with the said spring casings.

13. In a car, the combination of a truck 120 frame, a car body, journal boxes rigidly mounted on the said truck frame, elliptical springs mounted on the said journal boxes and extending in the direction of the length of the car, clips fastening the said elliptical 125 springs to the said journal boxes, spring casings attached to the car body, sets of helical springs mounted on the said casings

and connected with the free ends of the said helical springs, and draft bars pivotally connecting the said clips with the said spring casings.

5 14. In a car, a spring support comprising an elliptical spring, a spring casing adapted to support the car body and into which extends the free end of the said

elliptical spring, a rod carrying spaced cups, the upper cup resting on the free end of the 10 elliptical spring, and helical springs, of which one is interposed between the upper cup and the top of the casing and the other is interposed between the other cup and the bottom of the casing.

LEWIS ERNEST KEIL.
